CLAIM

We claim the ornamental design for a measuring device, as shown and described.

DESCRIPTION

FIG. 1 is a perspective view of a measuring device, such as a scale, having an interface embodying aspects of the invention.

FIG. 2 is a side view of the measuring device shown in FIG. 1.

FIG. 3 is a front side view of the measuring device shown in FIG. 1; and,

FIG. 4 is a top view of the measuring device shown in FIG. 1.

The present application is directed to the shape and contour of a measuring device of the design illustrated in the drawing.
